HEATING DEVICE AND COMBUSTION
PROCESS

Richard J. Waller, Bridgeport, Conn.

Application August 17, 1946, Serial No. 691,270

11 Claims. (Cl. 158—53)

1

This invention relates to heating devices, and more particularly to devices designed especially for the use of liquid fuels. It is a continuation-in-part of my copending application Serial No. 564,851 filed November 23, 1944, now Patent 2,497,282, Feb. 14, 1950.

An object of the invention is to provide a simple type of heating device that will burn liquid fuels very efficiently.

Another object of the invention is to provide a device of this character that is adapted particularly to utilize the industrial fuel oils.

A further object of this invention is to provide means for effecting substantially complete gasification of such fuel oils prior to their combustion.

Complete gasification is an essential requirement for ultra high efficiency of operation. When the industrial fuel oils are used the problems of securing such gasification are of greater complexity than with lighter fuels which flow readily and vaporize easily. It has been found advantageous to preheat the industrial fuel oils prior to their gasification. An object of this invention is to provide novel means for effecting such preheating which is embodied in the device itself, thereby eliminating the necessity for extra equipment.

The complete gasification of the fuel when spoken of in this specification and its claims means the production of homogeneous gaseous mixtures for combustion whose original components of fuel and air or other oxygen-containing gas are so blended or merged, that the fuel will not thereafter separate from such gaseous mixtures by liquefaction at moderate temperatures, and furthermore, that the fuel and oxygen-containing gas in the homogeneous gaseous mixtures are in the proper proportions for complete combustion in the absence of additional oxygen or oxygen-containing gas.

In effecting this gasification, in general, the liquid fuel is preheated and delivered under slight pressure and in vaporized condition through a nozzle located in proximity to a nozzle delivering air or other oxygen-containing gas hereinafter called entraining gas. This entraining gas entrains the fuel vapor, serving further to break up or atomize the vapor particles. Additional air or oxygen-containing gas hereinafter termed processing gas is delivered in the region of the nozzles and the entrained vapor, entraining gas and processing gas are delivered to expanding zones, the first of which is divergent and the next succeeding of which is larger in section than the

2

largest section of the divergent zone. In this second zone, the complete gasification occurs producing the desired gaseous mixtures for combustion which pass out of the said second zone through a burner nozzle and are burned externally of the second zone in a refractory shell which surrounds the burner nozzle. The refractory shell becomes incandescent. Part of its heat is radiated rearwardly and some of the hot products of combustion are circulated rearwardly of the shell, for fuel preheating purposes and for the purpose of heating portions of the expansion zones. The preheating of the fuel is effected by providing a preheating chamber so positioned as to receive heat radiated backwardly from the shell and also from rearwardly circulating hot products of combustion. In addition, the preheating chamber may further be heated electrically. Suitable ignition means also are provided.

20 A further object of the invention is to provide structure capable of operating as just described.

To the accomplishment of the foregoing and such other objects as may hereinafter appear, this invention consists in the novel construction and

25 arrangement of parts hereinafter to be described and then sought to be defined in the appended claims, reference being had to the accompanying drawing forming a part hereof, which shows merely for the purposes of illustrative disclosure, preferred embodiments of the invention, it being expressly understood, however, that changes may be made in practice within the scope of the claims without digressing from the inventive idea.

In the drawing in which similar reference characters denote corresponding parts:

30 Fig. 1 is an elevational view of one form of the device;

Fig. 2 is an end elevation viewed from the right-hand side of Fig. 1;

35 Fig. 2a is a fragmentary section taken along line 2a—2a of Fig. 1;

Fig. 3 is a longitudinal section of the device of Figs. 1 and 2 taken along line 3—3 of Fig. 2 and viewed in the direction of the arrows;

40 Fig. 4 is a longitudinal section taken along line 4—4 of Fig. 4a and viewed in the direction of the arrows;

Fig. 4a is an end view taken along line 4a—4a of Fig. 3 and viewed in the direction of the arrows;

45 Fig. 5 is a longitudinal section of a modified form of device taken along line 5—5 of Fig. 6 and viewed in the direction of the arrows;

Fig. 6 is an end elevation viewed from the right of Fig. 5;

Fig. 7 is a longitudinal section taken along line 7—7 of Fig. 6; and

Fig. 8 is a fragmentary section illustrating a modified means for feeding fuel to the preheating chambers of either of the devices of Fig. 1 or 5.

Referring to the drawing, and first to Figs. 1—4 inclusive, the heating device H comprises generally blender parts A and B wherein a fuel previously preheated as will be presently described is entrained with entraining air or other oxygen-containing gas, and treated with additional processing air or other oxygen-containing gas, an expansion chamber C connected with the blender parts by a diverging tubular portion D into which the fuel and gas mixture is discharged from the blender parts, an adjustable burner nozzle E, refractory material in the form of a cup or shell F arranged in conjunction with the burner nozzle E, a fuel preheating chamber G, and means for preheating such chamber all for purposes to be presently described.

The blender part A includes a casting 10 of suitable metal such as brass or the like. This casting 10 has a passage 11 extending longitudinally thereof and terminating at one end in a nozzle 12. The casting 10 has an enlarged recess 13 at one end into which the opposite end of passageway 15 opens. A tube or conduit 14 is secured in the recess 13 and connected to a source P of air or other oxygen-containing gas supply. A second passageway 15 extends longitudinally of the casting 10. This passageway 15 terminates at one end in recess 13 so that it communicates directly with the tube or conduit 14. The opposite end of the casting 10 has a recess 16 and the other end of passageway 15 terminates in this recess 16. A suitable spring-actuated valve 17 that is movable transversely of the passageway 15 serves to control the flow of gas from the supply source P through the passageway 15. This valve 17 normally rests upon a seat 18 closing off passageway 15. A pivoted cam lever 19 serves to raise the valve 17 from its seat 18 against the action of a spring 19a so that the valve 17 may be moved to open passageway 15 to any extent desired for a purpose presently to be described.

The blender part B comprises a tubular part 20 preferably of the same material as part 10. This part 20 is dimensioned to fit within the recess 16 of the part 10 and is secured in place as by welding or in other suitable ways. The bore of this part 20 is sub-divided into a cylindrical section 21, an inwardly tapering section 22, a second cylindrical section 23 of reduced diameter and a flaring section 24. The latter three sections resemble a Venturi arrangement. A shoulder 26 is defined between the larger cylindrical section 21 and the tapering section 22.

The nozzle 12 projects from the casting 10 into the cylindrical bore portion 23 of the blender part B. An annular flange 27 on the nozzle 12 is positioned to abut the shoulder 26. This flange has a plurality of distributing ports or orifices 28. The portion of bore 21 between the outlet end of passageway 15 and the flange 27 constitutes a distributing chamber for processing air or other oxygen-containing gas flowing thereto through passageway 15. The ports or orifices 28, preferably are uniformly distributed relative to the nozzle 12 for a purpose presently to be described. There may be six or more such ports, for example.

The tubular part 30 has the divergent cham-

ber D and is secured as by the nut 31 to the blender part B. The divergent tubular chamber D terminates in a substantially cylindrical expansion chamber C having an end plate or wall or deflection surface 35. This end wall is substantially a plane surface except at its center for a purpose presently to be described. A tubular extension 36 extends forwardly of the surface 35, being of substantially smaller diameter than and opening into the chamber C through the wall 35. This tubular extension is centrally located. It is threaded internally to receive parts of the burner nozzle E.

The preheating chamber G, in the embodiment shown, is defined by a shell 38 of substantially toroidal form carried conveniently upon the tubular member 36. This shell 38 is welded or otherwise secured to the surface of tubular member 36 to provide leak proof joints 39, 40. The shell 38 is traversed by two or more tubes 41 for purposes to be presently described. The shell 38 is spaced from the wall 35 for purposes to be presently described and the traversing tubes 41 extend rearwardly from the shell into the space between the shell 38 and the said wall 35.

Fuel is delivered to the preheating chamber G. To this end a fuel tube 46 and a surrounding jacket tube 47 extend into the chamber G through a wall of the shell 38. The jacketing tube 47 is of larger diameter than the fuel tube 46 providing a gas passageway 49 that surrounds the fuel tube 46. The fuel tube 46 is connected in the passage of a coupling member 50. A conduit 51 leads from the latter to a fuel source K. The jacketing tube 47 is connected to a coupling part 52 from which a conduit 53 leads either to the same air or oxygen-containing gas source P that delivers similar gas to the supply duct 14, or it may be connected to an independent source. It is to be understood that suitable control valves 54, 55 are provided somewhere in the conduits 51, 53 leading to the respective coupling members or parts 50 and 52.

The outlet 58 of the preheating chamber G is connected by a conduit 59 to a nozzle 60 which terminates in the region of air or other oxygen-containing gas nozzle 12 as will be presently described. The two nozzles 12 and 60 are disposed relative to each other so that flow of entraining gas from the nozzle 12 has an entraining and atomizing effect for purposes presently to be described. The conduit 59 passes through the chambers C and D.

A preheater 70 is provided. This preheater comprises a block 71 of insulating and heat-resisting material such as porcelain. An electrical heating coil 72 is supported in a groove 73 in the block and lies below the surface of the said groove. The block has holes 74 extending through it in this groove 73. The block 71 is positioned and supported suitably on the tubular member 36 with the heating coil exposed toward the shell 38 and in close proximity to the wall 38a of the latter so that heat radiated from the coil 72 will warm the preheating chamber 38 by heating of its wall 38a. The terminals of the coil are connected to leads 74, 75 which may be connected to a source of electrical power. The block is supported suitably from casing G as at 79.

The bottom Fa of the refractory cup or shell F has the overhanging flange or skirt Fb, which latter, when in abutment with the face 38b of the preheating shell 38, defines a chamber or recess 86. The tubes 41 open into the chamber 86 for a purpose presently to be described. The shell

F is secured in place, for example, by the threaded sleeve 81. This sleeve extends through an opening 82 in the shell bottom Fa, the sleeve 81 being headed at 81a so that it may be tightened after threading into the tubular member 36. The sleeve 81 is internally threaded to receive a tubular threaded portion 83 of the burner tip E. Passageways 84 in the tubular portion 83 of the tip E and grooves 85 are provided. The grooves 85 and the outer end of the sleeve 81 define passageways 83 of adjustable dimensions for egress of the combustible product from chamber C.

The bottom Fa of the shell has a recess or groove 88 to receive an electrical heating coil 90. This coil 90 is suitably supported in the recess and its terminals are connected to electrical leads 91, 92 which may be connected to a source of electrical power. This coil 90 functions primarily as an igniter as will be presently described.

Ports or passages 95 are provided which extend through the bottom Fa of the refractory shell F from one face to the other thereof. These passages are so positioned, as seen in Fig. 2 that parts of the starting or igniting coil 90 are visible therethrough for purposes presently to be described. These ports or passages 95 terminate on the outer face of the bottom Fa in the region of curvature 96 so that ledges or shoulders 97 (Fig. 3) are provided that lie in the path of combustible gases emitted from the passageways 86, so that a portion of such gases are deflected through the ports or passages 95 into the chamber 88 and into contact with the starting or ignition coil 90 for ignition purposes. When ignition has been established and the starting coil turned off, hot burning gases and hot products of combustion are deflected by the shoulders 97 into the chamber 88. Such burning gases or products of combustion circulate in this chamber 88 and heat the wall 38b of the preheating chamber G and some also pass through the tubes 41 providing further heat for the preheating chamber G. The gases emerging from tubes 41 are still hot and strike the end plate 35 of the expansion chamber C serving to heat the latter all for purposes presently to be described.

In operation of the device, the preheating coil 72 is connected to electric power so as to heat the preheating chamber G. The fuel valve 54 is opened so that fuel starts to flow into the preheater chamber G. The heat generated by the preheating coil 72, reduces the viscosity of the fuel delivered to the preheating chamber G and at the same time begins to vaporize it. The valve 55 is opened admitting air to the chamber G which mixes with the fuel therein to form a vapor that is a preheated mixture of fuel and air or other oxygen-containing gas. The air or other oxygen-containing gas admitted to preheater chamber G is regulated by valve 55 so that the said vapor under sufficient pressure is developed to force its delivery from the preheating and vaporizing chamber G through the conduit 59 to the vapor nozzle 60. This air is important because its presence increases the CO₂ content in the gaseous products at the burner. As the vapor emerges from the vapor nozzle 60, it meets with additional air or other oxygen-containing gas delivered by nozzle 12. This additional gas, which will hereinafter be referred to as entraining gas, entrains such vapor, atomizes any droplets in such vapor and moves with the entrained vapor first into the divergent chamber D, then into the cylindrical expansion chamber C and finally outwardly of the latter through tubular

member 36, tube 83, passageways 84 and passageways 86. During such movement, the vapor and entraining gas become intimately mixed to form a combustible gas mixture which is that emerging from the passageways 86. This combustible mixture is directed so that part of it strikes the shoulders 97 and is deflected through ports or passages 95 into contact with the ignition coil 90. When the latter has its leads 91, 92 connected to a power source, it becomes incandescent and ignites the combustible mixture. This ignition spreads backwardly through the ports or passages 95 to the combustible mixture emerging from passageways 86. Once such combustion has been established and the refractory shell F has become incandescent, the ignition coil 90 may be disconnected. Preheating coil 72 likewise may be disconnected after combustion has been started and operating temperatures have been reached. Provision not constituting part of the invention, may be made for the automatic energization and deenergization of the ignition coil 90 and of preheating coil 72.

The combustible mixture emerging at the burner nozzle E, so far described, may be described as "rich" because the amount of fuel therein relative to the air or other oxygen-containing gas in it is at a maximum. Once combustion has been established, the richness of this mixture can be reduced. This is accomplished by opening the valve 17 to the desired degree so that air or other oxygen-containing gas flows into distributing chamber 21 and from there through the ports 28 about the nozzle 12. This latter gas is conveniently referred to hereinafter as processing gas. The opening of the valve 17 to permit this processing gas to flow automatically reduces the vapor entrained by the entraining gas coming from nozzle 12, and thus the richness of the fuel gas mixture delivered to the chambers C and D as previously described. The processing gas is delivered through the ports 28 so that in the region of entrainment at the tips of nozzles 12 and 60 it is in the form substantially of an envelope. As the entraining gas, the entrained vapor and the enveloping processing air move through divergent chamber C and into expansion chamber D, intermixing commences which results eventually under operating conditions in complete homogenization of the vapor and air or other oxygen-containing gas so that the combustible product emerging from the passageways 86 at the burner E is homogeneous and completely gasified for utmost efficiency of combustion. Tests of such product show that the homogenization is substantially complete because fuel does not separate by liquefaction from samples of such product even at room temperature or lower. Combustion is complete even in the absence of additional oxygen or oxygen-containing gas at the burner E.

The burning of the combustible products externally of the expansion chamber C and primarily in the refractory cup F is a feature of the invention. This burning causes the refractory to become incandescent so that combustion will be maintained even after the starting coil 90 is disconnected from power. In order to maintain this incandescence, it will be understood that the velocity of the gasified combustible products emerging from passageways 86 must be maintained at a level necessary to maintain the required incandescence for perpetuation of combustion. This, for any given pressure of the air or oxygen-containing gas source is ultimately de-

terminated by the orifice passages 86. These in turn may be varied in the embodiment shown by adjustment of the part E in the threaded sleeve 81. Any other suitable adjustment may be provided.

During operation, the experienced operator will find that optimum gasification is obtained when a determined volume ratio is maintained between the entraining gas coming from nozzle 12 and the processing gas. This volume ratio will vary depending upon initial pressure conditions from the air or other oxygen-containing gas supply source P and the nature of the fuel used. The adjustability of the valve 17 permits variation of the ratio to meet different conditions. However, with any device embodying the invention, if it is designed to operate under a standard set of conditions, the valve 17 need be adjusted but once so that it can always be opened to that position necessary to create the proper determined ratio between the entraining gas and the processing gas. Test data indicate that the best results are obtained in operation when the relationship between the volume of entraining gas and the processing gas is of the order of 40 to 60.

A further important aspect of the invention is that successful operation and maximum efficiency depends upon maintenance of an elevated temperature at the end plate or wall 35 of chamber C. This wall or deflecting surface may be termed a "hot plate." If the heated products of combustion emerging from the tubes 44 have temperatures in excess of 1100° F., then the "hot plate" 35 will be sufficiently heated.

It will be understood, of course, that the wall or "hot plate" 35 is part of the metallic heat conductive material whose walls define the expansion chamber C and the divergent chamber D so that these walls in turn become warmed by heat conduction. The hottest region, of course, is in the neighborhood of the "hot plate" 35. If the parts have substantially the proportions shown, the maintenance of the "hot plate" 35 at its required elevated temperature range, insures adequacy of warming of the walls defining the chambers C and D so that complete gasification of the fuel with air or other oxygen-containing gas occurs before the combustion product emerges from the burner orifices 86.

Another important aspect of the invention lies in providing means to prevent the gases deflected by the "hot plate" 35 from moving back from the expansion chamber C into cooler portions of the divergent chamber D. It will be noted that the expansion chamber C increases abruptly in diameter relative to the largest diameter of the diverging portion D. The shoulder 100 thus provided functions to prevent the reentry of the gases deflected by the "hot plate" 35 into cooler portions of the divergent chamber D, serving as a deflector means.

It is well known that when a fluid hits a hard surface with considerable velocity in a direction generally perpendicular to the surface, the fluid spreads out in all directions in a thin sheet. If the surface is turned back as in a cup or a glass, the fluid, water for example, strikes the bottom inside of the glass, turns and follows along the surface of the sides and comes out of the glass in a cylindrical sheet.

The conditions in the chambers C and D are now considered.

The main fluid stream R comprising the vapor product emerging from nozzle 60, and entraining air or other oxygen-containing gas from the nozzle

12 and the processing gas impinges on the portion of the "hot plate" 35 in the region surrounding the orifice of the tubular member 36 in a direction more or less perpendicular to the said "plate" and is deflected. The deflected stream spreads in a thin sheet radially in all directions toward the walls of the chamber C as denoted by the arrows S. Then, in turn, the multiplicity of streams still denoted by arrows S formed by the radial dispersion turn and follow the inner surface of the chamber C back away from the "hot plate" 35, until they encounter the shoulder 100. The latter deflects them inwardly toward the oncoming stream R. This stream R has considerable velocity and drags streams deflected inwardly by shoulder 100 back toward the "hot plate" 35. This completes one round of the circulation cycle and turbulence results. In the course of this circulation, streams denoted by arrows S have picked up heat by scrubbing the "hot plate" and inner surfaces of the hottest portions of the chamber C adjacent to said "hot plate." They, too, pick up some heat from the conduit 59. When they meet the oncoming stream R, they impart some of their heat to it, thus preheating it before it reaches the "hot plate" 35.

A given portion of the stream R may complete a considerable number of cycles of circulation as streams S before passing out through tubular member 36 and the passageways 86. Some portions of stream R even may pass out directly but these portions will be small and negligible. The preheating in the chamber G further reduces the probability that such portions are not completely gasified. As the conduit 59, the "hot plate" 35 and adjacent side walls of the chamber C increase in temperature and approach their stable elevated operating temperatures, more and more heat is carried by the circulating currents or streams denoted by arrows S to the oncoming stream R so that under actual operating conditions substantially complete homogenization occurs in this oncoming stream R even before it reaches the "hot plate" 35. All or substantially all of the combustible product under operating conditions emerging from the passageways 86, thus is substantially homogeneous and completely gasified. It is thus seen that the deflection shoulder 100 is apparently of importance, because it assists in creating turbulence among other things. The deflection plate 35, also, assists in creating turbulence.

The orifices of the nozzles 12 and 60 should be in proper relationship for greatest stability of operation and optimum of efficiency of operation. A principal requirement is that the respective nozzle orifice axes should be co-planar and cross each other substantially at right angles and be substantially in the positions shown in the drawings.

A modified form of construction is shown in Figs. 5-7 inclusive. Therein, the tube 46' and its jacketing tube 47' are mounted at an angle. The tubes 46 and 47 of Figs. 1-4 inclusive may be similarly disposed if desired.

In Figs. 5-7 inclusive all parts bearing primed reference characters correspond with parts which are similarly designated but unprimed in Figs. 1-4 inclusive.

It will be noted that the tubular member 36' of Figs. 5-7 is shorter than the corresponding tubular member 36 of Figs. 1-4 inclusive. Likewise, the vaporizing chamber G' defined by the casing 38' is directly adjacent the "hot plate" 35' instead of being spaced therefrom as in Figs. 1-4

inclusive. The refractory cup or shell F' is secured to tubular member 36' in the same way as is shell F of Figs. 1-4 inclusive by parts of the burner E'. A tubular member 105 jackets the shell F' and extends rearwardly thereof to abut wall 35' and thereby permits tightening of the cup or shell F' in place. The ports 95' of the refractory shell permit radiation of heat and flow of burning gases of combustion backwardly there-through into space 89' against and about the walls of the casing 38' and also against and into contact with portions of the "hot plate" 35'. The ignition coil 90' functions identically as that of Figs. 1-4 inclusive. If desired, this coil can be maintained in energized state until the device reaches its normal operating state. During this time its heat will radiate backwardly to aid in maintaining the necessary temperature of the preheating or vaporizing chamber G'. When the operating state is reached, the heat from shell F' is sufficient to maintain chamber G' at its necessary temperature. In the alternative, some other conventional preheater arrangement may be provided for heating the preheating chamber G'.

The principles of operation of the device of Figs. 5-7 are substantially identical with that of the form shown in Figs. 1-4 inclusive.

The couplings 50, 50', 52, 52' and tubes 46, 46', 47, 47' provided in the modifications of Figs. 1-7 inclusive for feeding fuel and air from conduits 51 and 53 either to chambers 38 or 38' may be eliminated if desired and the valve controlled conduits 51 and 53 coupled directly and independently to either the chamber 38 or 38' as shown in Fig. 8. In the latter, the chamber 38'' has inlet nipples 106, 107 to which the respective valve controlled fuel feed line 51'' and air feed line 53'' are connected. Operation with such connections is the same as that already described.

In all modifications it will be seen, all parts are compactly arranged and coordinated so that part of the heat of combustion is efficiently used for preheating purposes enabling practicable use of the devices with commercial grades of fuels. The parts are so arranged that, when the device is being operated under required operating conditions, complete homogenization of the fuel with air or other oxygen-containing gas occurs. In other words, the combustible product emitted at the burner under such conditions is one in which no tendency to liquefaction of the fuel content exists at usual room temperatures or higher and wherein the combustible product is a gaseous homogeneous mixture of fuel vapor and oxygen-containing gas in the proper proportions for complete combustion in the absence of additional oxygen or oxygen-containing gas.

When the devices described are operating under design conditions the following conditions should exist:

Grade of fuel—#2 fuel oil

Rate of fuel supply—7.5 c. c. per minute

Pressure of gas supply from source P—6 inches of H₂O

Ratio of volumes of entraining gas to processing gas—1 cu. ft. per minute to 1.5 cu. ft. per minute, i. e. 40/60

Wattage of preheating coil 72 or coil 90 at 115 volts—300 watts

Temperature of coils 72 or 90—about 1200° F.

Temperature of preheating chambers G or G'—1100° F.

Temperature of "hot plate" 35—1100° F.

Temperature in chamber C next to "hot plate"

35—1000° F.

Temperature of refractory—2300° F.

5 These conditions may vary within a reasonable range depending upon the grade of fuel and air pressures used.

10 The devices shown have a rating of 15,000 B. t. u. per hour. There is no intention of limitation to such a rating. Devices of larger or smaller ratings may be manufactured simply by maintaining the proportionate dimensions of the various parts shown herein.

15 While specific embodiments have been shown, variations in structural detail are possible within the scope of the claims and are contemplated. There is no intention, therefore, of limitation to the exact details shown and described.

What is claimed is:

20 1. In a device of the character described, means for preheating liquid fuel to provide a fuel vapor, means for delivering liquid fuel to said preheating means, a nozzle means for delivering the vapor to said nozzle, a second nozzle in proximity to the first-named nozzle, means for delivering entraining gas through said second nozzle, means for delivering processing gas as an envelope in the region of said nozzles, a tubular member having a diverging chamber into which 25 the mixture of vapor, entraining gas and processing gas is delivered, and an expansion chamber directly adjacent said diverging chamber into which said mixture flows directly from said diverging chamber, burner means, a conduit arranged in a wall of said expansion chamber and communicating with said burner means, and a refractory shell arranged adjacent the said burner means, said shell having openings for delivering part of the heat of combustion rearwardly toward said wall.

30 2. In a device of the character described, means for preheating liquid fuel to provide a fuel vapor, means for delivering liquid fuel to said preheating means, a nozzle, means for delivering the vapor to said nozzle under pressure, a second nozzle in proximity to said first-named nozzle, means for delivering entraining gas through said second nozzle, the two nozzles being disposed so that the entraining gas moving past the vapor nozzle will entrain said vapor, means for delivering processing gas in the region of said nozzles, a tubular member having a diverging chamber into which the vapor, entraining gas and processing gas are delivered as a mixture, and an expansion 35 chamber directly adjacent said diverging chamber into which the mixture flows directly from said diverging chamber, walls of said expansion chamber defining deflecting surfaces for effecting turbulence of the mixture flowing to said expansion chamber from said diverging chamber, burner means, a conduit arranged in a wall of said expansion chamber and communicating with said burner means, a refractory shell arranged adjacent the said burner means, said shell having openings for delivering part of the heat developed as a result of combustion rearwardly toward said expansion chamber, said means for preheating said liquid fuel being positioned intermediate said shell and said expansion chamber.

40 3. In a device of the character described, a casing defining a preheating chamber for liquid fuel, means for delivering liquid fuel to said chamber, electrical means for vaporizing liquid fuel in said chamber, a nozzle, a conduit for delivering vapor from said casing to said nozzle,

75

a second nozzle in proximity to said first-named nozzle, means for delivering entraining gas through said second nozzle, the two nozzles being disposed so that the entraining gas moving past the vapor nozzle will entrain vapor emitted therefrom, means for delivering processing gas in the region of said nozzles, valve means for regulating the delivery of said processing gas, a tubular member having a diverging chamber and an expansion chamber, the vapor, entraining gas and processing gas flowing into these chambers, walls of said expansion chamber defining deflecting surfaces creating turbulence to intermix the vapor, entraining gas and processing gas completely, burner means, a conduit from said expansion chamber to said burner means, a refractory shell surrounding said burner means, said shell having openings for delivering part of the heat of combustion developed at the burner means rearwardly toward said expansion chamber to heat the latter, the heating of said expansion chamber and the turbulence created therein causing the intermixed vapor, entraining gas and processing gas therein to form a completely gasified combustible product which is delivered through said second conduit and emitted from said burner and burned in said shell, and electrical ignition means for starting combustion at the burner.

4. A device of the character described, comprising a member having a divergent chamber and an expansion chamber directly adjacent said divergent chamber, a burner, a conduit providing communication between said expansion chamber and said burner, a refractory shell surrounding said burner, a casing defining a fuel preheating chamber positioned between said refractory shell and a wall of said expansion chamber, means for delivering liquid fuel to said preheating chamber, means for heating said preheating chamber to vaporize fuel delivered thereto, a nozzle, conduit means passing through said divergent and expansion chambers to connect said nozzle to said preheating chamber so that vapor emerges from the nozzle, a second nozzle in proximity to said first-named nozzle, means for delivering entraining gas through said second nozzle to entrain the vapor, means for delivering processing gas in the region of said nozzles, valve means for controlling the delivery of said processing gas, the said gases and vapor flowing into said divergent chamber and then into said expansion chamber, and becoming a gasified combustible product prior to emission at the burner, and means for igniting said combustible product.

5. A device of the character described, comprising a member having an expansion chamber, a burner, a refractory shell surrounding said burner, a casing defining a fuel preheating chamber positioned between said shell and said expansion chamber, means for delivering liquid fuel to said preheating chamber, electrical means for heating said preheating chamber to vaporize said liquid fuel, means for mixing the vaporized fuel with oxygen-containing gas and effecting gasification of the mixture in said expansion chamber to produce a gasified product, said burner communicating with said expansion chamber so that the gasified product is emitted therefrom, and means for igniting said gasified product upon emission from said burner, the burning of said gasified product taking place ex-

ternally of said expansion chamber and within said refractory shell.

6. A device of the character described, comprising a member having a divergent chamber and an expansion chamber directly adjacent said divergent chamber, a burner, a conduit connecting said burner means with said expansion chamber, a refractory shell surrounding said burner, a casing defining a fuel preheating chamber positioned between said refractory shell and a wall of said expansion chamber, means for delivering liquid fuel and oxygen-containing gas to said preheating chamber, means for heating said preheating chamber to vaporize fuel delivered thereto, a nozzle, conduit means passing through said divergent and expansion chambers for delivering vapor under pressure from said preheating chamber to said nozzle, a second nozzle in proximity to said first-named nozzle, means for delivering entraining gas through said second nozzle to entrain the vapor emerging from said first-named nozzle, means for delivering processing gas in the region of said nozzles, and valve means for controlling the delivery of said processing gas, the said gases and vapor flowing into said divergent chamber and then into said expansion chamber prior to emission and burning at the burner.

7. A device of the character described, comprising a member having an expansion chamber, a burner, a refractory shell surrounding said burner, a casing defining a fuel preheating chamber positioned between said shell and said expansion chamber, means for delivering liquid fuel to said preheating chamber, means for heating said preheating chamber to vaporize said liquid fuel, and means for mixing the vaporized fuel with oxygen-containing gas and effecting complete gasification of the mixture in said expansion chamber to produce a gasified product, said burner communicating with said expansion chamber so that the gasified product is emitted from the burner and may be burned entirely externally of said expansion chamber and within said refractory shell.

8. A device of the character described comprising a member having an expansion chamber, a burner externally of said chamber, a refractory shell surrounding said burner, said shell having a wall with passages, a casing defining a fuel preheating chamber positioned between said shell and said expansion chamber, said shell being recessed to define a space between said casing and its said wall into which said passages are open, an electric starting coil in said space in proximity to said passages, an electric heating coil in proximity to said casing for preheating said casing and vaporizing fuel therein, and means for delivering liquid fuel to said preheating chamber for vaporization therein and means for mixing oxygen-containing gas with the vaporized fuel and means for effecting a substantially inseparable gaseous mixture of vaporized fuel and oxygen-containing gas in said expansion chamber, a conduit connecting said burner with said expansion chamber for delivering the substantially inseparable gaseous mixture from said expansion chamber for emission at said burner and for burning at said burner and externally of said expansion chamber and within said refractory shell.

9. That improvement in the process of combustion of liquid fuel comprising the steps of heating liquid fuel to vaporize it, delivering the vapor so formed under pressure to an entrain-

13

ing region, there entraining such vapor with oxygen-containing entraining gas, delivering oxygen-containing processing gas into the region of entrainment, then moving the gases and vapor as a primary stream through two expanding zones the first of which is divergent and the second of which is abruptly larger in section than the largest section of the divergent zone, impinging the said stream against a heated deflection surface in said second zone to deflect portions thereof along the surface of said second zone, redeflecting the deflected portions in said second zone to meet the primary stream entering said second zone thereby effecting turbulence of the gases and vapor in said second zone and intermixing thereof to produce a homogeneous gasified combustible product, and thereafter burning the gasified combustible product in a zone separated from the two first-named zones.

10. That improvement in the process of combustion of liquid fuel comprising the steps of heating liquid fuel to vaporize it, delivering the vapor so formed under pressure to an entraining region, there entraining such vapor with oxygen-containing entraining gas, delivering oxygen-containing processing gas into the region of entrainment, then moving the gases and vapor as a primary stream through two expanding zones the first of which is divergent and the second of which is abruptly larger in section than the largest section of the divergent zone, impinging the said stream against a heated deflection surface in said second zone to deflect portions thereof along the surface of said second zone, redeflecting the deflected portions in said second zone to meet the primary stream entering said second zone thereby effecting turbulence of the gases and vapor in said second zone and intermixing thereof to produce a homogeneous gasified combustible product, delivering the homogeneous gasified combustible product to a third zone separated from the second zone, burning the homogeneous gasified combustible product in said third zone to provide hot products of combustion, and delivering part of the hot products of combustion to heat said deflection surface.

11. In a device of the character described, means defining a preheating chamber for liquid fuel, means for delivering liquid fuel to said chamber, means for delivering oxygen-containing gas to said chamber, means for heating said

14

chamber for vaporizing the fuel in said chamber, a nozzle, a conduit for delivering a mixture of fuel vapor and oxygen-containing gas from said chamber to said nozzle, a second nozzle in proximity to said first-named nozzle, means for delivering entraining gas through said second nozzle, said two nozzles being disposed so that the entraining gas moving past the vapor nozzle will entrain the vapor and oxygen-containing gas emitted therefrom, means for delivering processing gas adjacent said nozzles, means for regulating the ratio of the volumes of the entraining gas and of the processing gas, a tubular member having a diverging chamber and an expansion chamber into which said vapor and gases are delivered, walls of said expansion chamber defining deflecting surfaces for effecting turbulence and intermixing of the vapor and gases delivered thereto, means for heating said expansion chamber so that the turbulent vapor and gases delivered thereto become a homogeneous gasified combustible product, and means for burning such gasified combustible product externally of said expansion chamber.

RICHARD J. WALLER.
